Patented Nov. 7, 1916.
2 SHEETS—SHEET 1.

UNITED STATES PATENT OFFICE.

JOHN L. CREVELING, OF NEW YORK, N. Y.

TELEPHONE APPLIANCE.

1,204,136.

Specification of Letters Patent. Patented Nov. 7, 1916.

Application filed July 27, 1908. Serial No. 445,594.

To all whom it may concern:

Be it known that I, JOHN L. CREVELING, a citizen of the United States, residing in the city, county, and State of New York, have

5 invented a certain new and useful Improvement in Telephone Appliances, of which the following is a specification, reference being had to the drawing forming a part thereof.

My invention pertains to that class of devices intended to be used in connection with the receiver of an ordinary telephone and has for its particular object to provide means for rendering impulses emitted by an ordinary telephone receiver audible in both 15 ears instead of one only, as is usual, and also to cut out outside noises which ordinarily tend to confuse a person having a single receiver to one ear and the other ear open to outside impulses.

20 It is a further object of my invention to provide an inexpensive device which may fulfil the above functions and be readily applied to the ordinary receivers now in use without defacing the same and also to provide a device which may be permanently attached to the receiver or attached at such times as desired with as little inconvenience as possible.

Figure 1 is a side elevation and partial 30 section of an ordinary Bell telephone receiver together with one form of device embodying my invention applied thereto, shown partially in section. Fig. 2 is a front elevation of one means for attaching my device 35 to the ordinary receiver. Fig. 3 is a side elevation of the attaching means shown in Fig. 2.

In Fig. 1 (1) represents the body portion 40 of the ordinary Bell telephone receiver provided with the threaded portion (2), diaphragm (3) and ear piece (4) having an annular flange (5) serving to clamp the diaphragm in place and define the cavity (6) with which communication is established 45 by the aperture (7). (8) represents an ear piece which may be identical with the ear piece (4) with exception of the opening or cavity (9) which communicates with the nipple (10) to which is attached the sound tube (11) terminating in the nipple (12) which is attached to the ear piece (13) so as to communicate with the interior of the cavity (14) thereof. The ear piece (8) is shown as held in place against the receiver 50 (1) as by means of clips (16) carried by a spring ring as indicated in section by (17).

In Figs. 2 and 3 (16) represents the clips as shown in Fig. 1 carried by the spring ring (17) which may be opened and sprung upon the ear piece (8) if desired. 60

The practical operation of my improved telephone appliance is substantially as follows; reference being had particularly to Fig. 1. If desired, the telephone receiver (1) may be used in the regular way without 65 the use of my appliance until such times as it may be desirable to cut out outside noises and render the sound emitted by the receiver more easily audible. At such times the ear piece (8) may be placed against the ear 70 piece (4) of the receiver and held firmly against one ear of the listener and the ear piece (13) held against the other ear.

Then the sound impulses emitted by the receiver will be transmitted to the operator 75 through the aperture (7) and through cavity (9) tube (11) to cavity (14) causing an effect on each ear in such manner as to make the vibrations of the diaphragm (3) much more plainly audible and the ear 80 piece (13) will also serve to cut out outside noises.

If desired to permanently attach my appliance to the receiver (1), the ear piece (4) may be removed and the ear piece (8) 85 screwed upon the threaded portion (2) in its place. With this arrangement sound may be carried to each ear in an obvious manner. If desired to attach my appliance to the ordinary receiver in such manner 90 that it will stay attached thereto and at all times be readily and quickly removable the spring device as shown in the figures may be used in the following manner. The spring ring (17) may be opened and sprung over 95 the ear piece (8) in such manner as to firmly grip the same. Then if the ear piece (8) be pressed against the receiver (1) the clips (16) will spring over the edge of the ear piece (4) and hold the ear piece (8) in 100 place as shown in Fig. 1 and thus the appliance will remain attached to the receiver until purposely separated as desired.

It will be noted that when the ear piece (8) is held upon the ear piece (4) by the 105 clips (16) the same may be rotated about the ear piece (4) with little difficulty; therefore, if in picking up the instrument and placing the ear piece (8) to the ear, the tube (11) should happen to come in an undesirable position, as for example between the face of the user and the telephone trans-

mitter, the ear piece (8) may readily be re-
volved upon the receiver against which it is
merely held by the clip (16) and the tube
(11) brought to a desirable position. In
5 the use of this type of instrument this is a
very desirable feature.

I do not wish in any way to limit myself
to any particular constructions shown in the
drawing which is merely an illustration of
10 some forms of devices embodying my in-
vention and from which great variation may
be made and still be within the scope of said
invention.

Having thus described my invention, what
15 I desire to protect by Letters Patent is as
set forth in the following claims, to wit:—

1. An attachment for a telephone receiver
ear piece adapted to operatively engage the
same, comprehending an attachment ear
20 piece having a spring ring encircling and
gripping the same provided with members
adapted to engage the telephone receiver ear
piece to detachably hold the attachment ear
piece in operative relation to said receiver
25 ear piece.

2. An attachment for telephone receivers
comprising an ear piece, a spring ring en-
circling and gripping said ear piece, said
ring being provided with members for oper-
30 atively engaging a telephone receiver to hold
said attachment ear piece in operative rela-
tion thereto.

3. The combination with a telephone re-
ceiver having an ear piece, of an attachment
35 ear piece provided with engaging means
whereby it is retained in operative relation
with said receiver ear piece, said engaging
means comprehending a spring ring encir-
clining and gripping said attachment ear piece
40 and having projecting members for engag-
ing the telephone receiver ear piece to hold
said ear pieces in operative relation with
each other.

4. An attachment for a telephone receiver
45 ear piece adapted to operatively engage
the same, comprehending an attachment ear
piece having a spring ring encircling and
gripping the same, said ring being provided
with members engaging said attachment ear
50 piece to prevent lateral movement thereon,
and also provided with members adapted to
engage the telephone receiver ear piece to

detachably hold the attachment ear piece
in operative relation to said receiver ear
piece.

55

5. An attachment for telephone receivers
comprising an ear piece, a spring ring encir-
clining and gripping said ear piece, said ring
being provided with members for preventing
lateral movement of said ear piece within
60 said ring, and also provided with members for
operatively engaging a telephone receiver
to hold said attachment ear piece in oper-
ative relation thereto.

60

6. The combination with a telephone re-
ceiver having an ear piece, of an attachment
ear piece provided with engaging means
whereby it is retained in operative relation
with said receiver ear piece, said engaging
means comprehending a spring ring encir-
70 clining said attachment ear piece and having
inwardly turned members on opposite sides
thereof engaging said ear piece and also
having projecting members for engaging
the telephone receiver ear piece to hold said
75 ear pieces in operative relation with each
other.

70

7. The combination with a telephone re-
ceiver having an ear piece provided with
a sound transmitting aperture, of an at-
tachment ear piece adapted when placed be-
tween the receiver ear piece and the ear
80 of a user to transmit sound waves from
said aperture to said ear, and having a
second ear piece, means for carrying sound
waves from the receiver thereto, and means
85 for holding the attachment ear piece in oper-
ative relation to the receiver ear piece com-
prehending a member encircling the attach-
ment ear piece and tending to grip the same,
90 said member being provided with inwardly
extending members engaging said attach-
ment ear piece to prevent lateral movement
with respect to said encircling member and
means carried by said encircling member
95 for engaging the receiver ear piece and hold-
ing the said ear piece and the attachment
ear piece in operative relation with each
other.
